UNITED STATES PATENT OFFICE

94,359

DESIGN FOR A PICTURE FRAME

David E. Roganson, Short Beach, Conn.

Application September 10, 1934, Serial No. 53,247

Term of patent 14 years

To all whom it may concern:

Be it known that I, David E. Roganson, a citizen of the United States, residing at Short Beach, in the town of Branford, county of New Haven, State of Connecticut, have invented a new, original, and ornamental Design for a Picture Frame, of which the following is a specification, reference being had to the accompanying drawing, forming part thereof.

The figure is a perspective view of a picture frame showing my new design.

What I claim is:

The ornamental design of a picture frame as shown.
